UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

WINDING MACHINE.

Application filed November 27, 1923. Serial No. 677,209.

To all whom it may concern:

Be it known that I, ALONZO E. RHOADES, a citizen of the United States, and a resident of Hopedale, county of Worcester, 5 State of Massachusetts, have invented an Improvement in Winding Machines, of which the following description, in connection with the accompanying drawing, is a specification, like characters on the drawing 10 representing like parts.

This invention relates to improvements in winding machines for binding a travelling chain of yarn preparatory to boiling, dyeing, bleaching, or otherwise treating the 15 yarn.

Usual machines of this type comprise a tubular guide for the chain which leads through a rotatable winding device having a cylindrical hub provided at its lower end 20 with a support for the binding material and at its upper end with a winding plate having a delivery eye through which the binder is guided. As the hub of the winding device is necessarily of considerable length 25 difficulty has been experienced in inserting the numerous free ends of the chain through the long passage in the hub.

One of the objects of the invention is to provide a standard for supporting the 30 binder guide which will present a longitudinal opening or openings through which access may be obtained to the chain in order that the end may be more readily introduced through the winding mechanism.

A further object of the invention is to provide the tubular chain guide, and preferably also the passage in the winding plate, with a lining of material which will not 35 corrode, stain or otherwise affect the yarn of the chain.

Another object of the invention is to provide a more rigid winding mechanism than heretofore employed.

In prior constructions the binder is led 45 through a delivery eye in the winding plate and thence beneath, or beneath and over, one or more felt or fibre pads, the ends of which are secured to the winding plate in order to impose a proper tension upon the binder. In such constructions it is necessary 50 to raise the central portion of the pad to insert the end of the binder therebeneath, an operation which is inconvenient and requires considerable time.

A further object of the present invention 55 is to provide a novel tension mechanism which may be readily threaded.

Other objects and features of the invention will more fully appear from the following description and the accompanying drawings and will be particularly pointed out in the claims.

In the drawings:

Fig. 1 is a side elevation of a winding machine embodying the invention;

Fig. 2 is a plan view of the same, a portion of the hollow bed of the machine being broken away to illustrate the driving mechanism for the winding device; and,

Fig. 3 is a vertical sectional view in a 70 plane extending transversely of the bed and axially of one of the winding mechanisms.

The winding machine comprises a frame having legs 1 which support a preferably rectangular box-like bed 2 having a cover 75 3. The base 4 of the bed has secured to it a plurality of downwardly extending cylindrical brackets 5 which, in the machine shown in the present illustration, are three 80 in number, but, of course, may be of any other desirable number. A tubular chain guiding member 6 fits within and is rigidly secured to the lower end of each of the cylindrical brackets. The tube 6 is provided with a lining or bushing 7 of anti-corrosive 85 material. The term "anti-corrosive" is used herein as meaning a material which will not become rusted, corroded, or otherwise affected by moisture or chemicals to produce a product which will abrade, stain, or otherwise affect the yarn which is passed through it.

The bracket 5 is counterbored to provide a step bearing 8 for a sleeve 9 which extends upwardly through the bed and is rotatably mounted upon the tubular chain guide. The sleeve 9 has secured to it a gear 10 which is located in the chamber 11 of the hollow bed. Pinions 12, suitably mounted upon studs 13 extending upwardly from the 100 base of the bed, serve to cause the rotation of the several winding devices from a gear 14 which is also located in the chamber 11 of the hollow bed and is mounted upon a vertical shaft 15 journaled in suitable bearings in the bed and a lower standard 16 and which is provided with a bevelled pinion 17 which meshes with a bevel-

elled gear 18 upon a suitable driving shaft 19 which is mounted in the standard 16. The sleeve 9 has also affixed to it the hub 20 of a support 21 for the binder.

- 5 The binder support as illustrated herein is in the form of a circular disk having a downwardly extending flange and provided near its periphery with an upwardly extending preferably conical stud or spindle 22 upon which a cop, ball or spool of binder 23 may be mounted. The binder is carried from the cop, ball or spool upwardly through a delivery eye 24 in a winding arm or plate 25 which as illustrated herein is in 10 the form of a circular disk to provide a counterbalanced construction and which is mounted at the upper end of a standard 26 which extends upwardly from the binder support 21.
- 15 In previous constructions the winding plate 25 has been connected to the binder support by a cylindrical hub. In the present invention the standard 26 which supports the winding plate presents a longitudinal opening to permit access to the chain of yarn.

20 The preferred form of standard is in the form of a longitudinal section of a hollow truncated cone having at its lower end a laterally extending flange 27 which is secured to the binder support 21 by suitable machine screws 28 and at its upper end a laterally extending flange 29 which is suitably secured to the under side of the winding plate 25. The winding plate 25 is provided with a passage for the chain in axial alinement with the tubular chain guide 6 and preferably the wall of the passage in the winding plate is provided with 25 a bushing 30 of anti-corrosive material, of the character heretofore described, such, for example, as brass or bronze.

25 By reason of this construction the end of the chain can be readily inserted upwardly through the lower end of the tubular chain guide and before the ends of the yarn become massed as they are pressed upwardly the end of the chain can be grasped by the operator and drawn upwardly and easily inserted through the aperture in the bushing 30 which lines the passage through the winding plate. By reason of this construction a considerable inconvenience in threading the yarn chain through the winding mechanism is avoided and the time of the operator saved. Furthermore the smooth surface of the lining of the tubular guide and of the passage through the winding plate facilitates the insertion of the end of the yarn chain.

30 Another object of the invention is to provide an improved tension device for the binder comprising a construction which can be readily threaded. The preferred tension device which is illustrated herein comprises

a pair of fingers 31 and 32 which extend in parallelism with the winding plate 25 and are located adjacent thereto. One end of each of the fingers 31 and 32 is bent at right angles to the plane in which the fingers lie and provided with a reduced portion which extends through a suitable hole in the plate and is secured to the plate by a nut 33 upon said reduced end portion and which abuts against the under face of the winding plate 25. The free ends 34 and 35 of the fingers 31 and 32 respectively are curved outwardly with relation to the delivery eye 24 so that the binder will not slip over the ends of the fingers. 70 75 80

When threading the binder it is merely necessary to pass the end of the binder upwardly through the delivery eye 24, thence over the fingers 31, thence under the finger 31 and beneath the other finger 32 and 85 thence over the finger 32 and around the chain which has been inserted through the tubular chain guide and the passage in the winding plate.

90 The winding machine illustrated herein is provided with the usual plate 36 having guiding apertures 37 for the chains which direct the same around a roller 38 and from which they are led upwardly through the stationary tubular chain guide and thence through 95 the winding mechanism as above described.

95 In the operation of the machine the winding mechanism is driven at an appropriate speed to produce the proper winding of the binder around the travelling chain during its progress upwardly through the tubular guide and winding mechanism. Thus the yarns of a chain may be securely bound together in such a manner that they will not become separated or tangled during the 100 105 boiling, dyeing, bleaching, or other processes.

110 The winding is evenly applied so that it can be readily unwound in the usual types of unwinding machines which are well known in the art.

115 It will be understood that the embodiment of the invention disclosed herein is of an illustrative character and is not restrictive and that various changes in form, proportion, construction and arrangement of parts may be made within the spirit and scope of the following claims.

120 Having thus described the invention, what is claimed as new, and desired to be secured by Letters Patent, is:

- 125 1. A winding machine for binding a travelling chain of yarn comprising a stationary tubular guide for the chain, a support for the binder rotatable about said tubular chain guide and having a binder supporting spindle located at a distance from the axis thereof, a standard extending upwardly from said support presenting a longitudinal opening to permit access to 130

- said chain and provided at its upper end with a passage for the chain in axial alinement with said tubular chain guide and with means for guiding the binding located 5 at a distance from said passage operable to wind the binder upon the chain beyond the end of said standard.
2. A winding machine for binding a travelling chain of yarn comprising a stationary tubular guide for the chain, a support for the binder rotatable about said tubular chain guide and having a binder supporting spindle located at a distance from the axis thereof, a standard comprising 10 15 20 25 30 35 40 45 50 55 60 65 70 75 80 85 90 95 a longitudinal section of a hollow truncated cone secured at its lower end to said binder support and extending upwardly therefrom and presenting a longitudinally extending opening to permit access to said chain, a winding member secured to the upper end of said standard having a passage for the chain in axial alinement with said tubular chain guide and provided with means located at a distance from said passage for guiding the binder operable to wind the binder upon the chain beyond the end of said standard.
3. A winding machine for binding a travelling chain of yarn comprising a stationary tubular chain guiding member having a lining of anti-corrosive material, means for supporting and guiding the binding material rotatably mounted upon said chain guiding member and means for rotating said binder supporting and guiding means.
4. A winding machine for binding a travelling chain of yarn comprising a stationary tubular guide for the chain having a lining of anti-corrosive material, a support for the binder rotatable about the axis of said tubular chain guide, a standard extending upwardly from said support presenting a longitudinal opening to permit access to said chain and provided at its upper end with a winding plate having a passage provided with a lining of anti-corrosive material for said chain in axial alinement with said tubular chain guide and a delivery eye in said plate located at a distance from said passage for guiding the binder.
5. A winding machine for binding a travelling chain of yarn comprising a stationary tubular chain guiding member, a binder support rotatably mounted on said tubular member, a standard extending upwardly from said binder support provided at its upper end with a winding plate having a passage for said chain and a delivery eye for said binder located at a distance from said passage, fingers secured to said plate located adjacent to and upon opposite sides of said delivery eye and having their free ends curved outwardly in opposite directions with respect to said eye operable to impose a proper tension upon the binder and adapted to be readily threaded.
6. A winding machine for binding a travelling chain of yarn comprising a hollow bed, a bracket secured to the under face of said bed, a vertical tubular chain guide rigidly secured to said bracket and extending upwardly therefrom, a sleeve rotatably mounted upon said tubular chain guide, a step bearing for said sleeve in said bracket, a gear located within said hollow bed and secured to said sleeve, a binder supporting member secured to said sleeve and located above said bed, a standard extending upwardly from said binder supporting member having at its upper end a winding plate having a passage for the chain in axial alinement with said tubular chain guide and provided with a delivery eye for said binder located at a distance from said passage.

In testimony whereof, I have signed my name to this specification.

ALONZO E. RHOADES.
